UNITED STATES PATENT OFFICE.

DANIEL FORBES, OF BROOKLYN, NEW YORK, ASSIGNOR TO GEORGE H. HIBBLER, OF SAME PLACE.

DESIGN FOR THE ORNAMENTATION OF GLASSWARE.

SPECIFICATION forming part of Design No. 17,086, dated February 8, 1887.

Application filed December 4, 1886. Serial No. 220,754. Term of patent 14 years.

To all whom it may concern:

Be it known that I, DANIEL FORBES, of Brooklyn, county of Kings, and State of New York, have invented and produced a new and original Design for Ornamentation of Glassware, of which the following is a full, clear, and exact description, reference being had to the accompanying drawing, and to the letters of reference marked thereon.

10 My design relates to the ornamentation of all articles of glassware, and for convenience is illustrated upon a bowl or deep dish, as shown in the accompanying drawing, forming part of this specification, in which drawing the 15 single figure is an elevation.

The design may be described as follows: The exterior surface of the bowl or dish is divided into about equal portions or bands by a series of horizontal channels, of which A A,

20 A A, &c., are the bottom lines. These channels are V-shaped. Spiral or inclined channels of similar shape, of which the bottom lines are B B, B B, &c., B' B', B' B', &c., extend from top to bottom and cross each other

25 at about right angles, crossing the horizontal channels at other angles. These are the principal channels, and they divide the surface so as to leave the truncated six-sided pyramids a a at substantially regular intervals in each

30 horizontal band. The upper or outer surfaces of these pyramids are preferably left plain or smooth, as shown; but they may be ornamented in any desired manner. They are commonly known as or called "hobnails," from their 35 general shape. In the horizontal bands and between the hobnails are two geometrical figures, as b b, called, for convenience, "rosettes." These are formed by V-shaped channels crossing each other through the center of the ro-

40 sette and by marginal channels, which together divide the rosettes into triangular pyramids. In the inclined bands or the parts between the principal inclined or spiral channels two rosettes occur between any two hob-

nails, same as in the horizontal bands. The 45 spaces between the rosettes and hobnails are relieved by triangular pyramids, so that the entire intervening spaces are supplied with and ornamented by symmetrically-disposed pyramids, each of which is a prism.

50 The arrangement of the rosettes and hobnails is such that in any horizontal row or band two hobnails are separated by two rosettes, and a similar arrangement occurs in each inclined row or band, hobnails in one 55 row being located opposite the space between the rosettes in the adjacent rows, affording a pleasing contrast and obviating a monotonous sequence of single hobnails and rosettes.

The upper margin of the bowl or dish may 60 be ornamented by the rounded portions, as c c, and pointed portions, as d d.

I desire it understood that the design is not limited to any particular article of glassware.

Having now fully described my design, what 65 I claim as new, and desire to secure by Letters Patent, is—

1. The design for the ornamentation of glassware, consisting of the rosettes and the hobnails disposed and arranged in the horizontal 70 and inclined bands, so that in each band the hobnails are separated by a pair of rosettes, substantially as shown and described.

2. The design for the ornamentation of glassware, consisting of the rosettes and hobnails 75 disposed and arranged in the horizontal and inclined bands, so that in each band the hobnails are separated by a pair of rosettes and the notched upper margin, substantially as shown and described.

In testimony that I claim the foregoing I have hereunto set my hand in the presence of two witnesses.

DANIEL FORBES.
